UNITED STATES PATENT OFFICE

WALTER B. ANDERSON, OF MAPLEWOOD, NEW JERSEY, ASSIGNOR TO DAVID LUPTON'S SONS COMPANY, OF PHILADELPHIA, PENNSYLVANIA, A CORPORATION OF PENNSYLVANIA

THRESHOLD OR SILL

Application filed June 21, 1928. Serial No. 287,171.

This invention relates to thresholds or sills for swinging closures such as doors or casement windows, especially to doors or windows of metallic construction.

5 My invention is directed toward provision of a threshold or sill capable of adaptation without necessity for structural change, to either inwardly or outwardly opening closures.

10 In connection with thresholds or sills generally, and particularly to a type characterized by adaptability in the manner indicated, I further aim to provide for effective trap-
page and disposal of drip water due to con-
densation on the insides of the closures, as
15 well as for positive exclusion of water, wind
and dust along the lower edges of the
closures.

Still further objects of this invention and
20 advantages accruing thereto will be apparent
from the detailed description which follows.

In the drawings, Fig. I is a part sectional
25 view of an outwardly opening door or casement
window structure with my improved
threshold or sill adapted thereto.

Fig. II is an illustration similar to Fig. I
showing the threshold or sill adapted to an
inwardly opening closure.

With more detailed reference to these illus-
30 trations, the numeral 5 comprehensively
designates the threshold or sill of my inven-
tion, and 6, the closure which may be a door
or a window sash pivotally hung either along
35 its upper edge, or along one of its vertical side
edges. In the present instance, the closure
6 is shown as constructed from metal with
side rails 7, and a bottom cross rail 8 of chan-
nel section.

The threshold 5 is likewise constructed
40 throughout from metal, and embodies a base
member 9 with an associate closure stop mem-
ber 10 which is reversible on the base mem-
ber to enable adaptation of the threshold or
45 sill to either outwardly or inwardly open-
ing closures, as later on more fully explained.
As shown, the base member 9 is of shallow
channel section with its top surface sloping
50 symmetrically downward at a slight angle
to the horizontal from opposite sides of a
central or medial ridge 11 as at 12, 13 the

surface 13 being however interrupted by an
additional ridge or abutment projection 14
which extends parallel to said medial ridge
11. The stop member 10 is considerably nar-
rower in width than the base member 9, but, 55
like it, fashioned to channel section for
capacity to bridge the ridge 11, and for place-
ment off center to either side of the latter
as required, under the two different condi-
tions of use. Upstanding from the member 60
10 are projections 15, 16 spaced by an interval
17 that serves as a gutter to trap drip water
from the closure 6. The projection 15 con-
stitutes the stop abutment proper for the clo-
sure 6, and, to this end, coacts with a bottom 65
flange 18, afforded by an angle piece 18^a, that
is secured by screws to the outer flange 8^a of
the bottom rail 8 of said closure. The bot-
tom flange 18 is received in a lateral hollow
19 of the stop projection 15, which houses a 70
weathering strip 20 to contact with said
flange. This weathering strip 20 is con-
structed from thin springy sheet metal—
preferably of non-corrosive metal such as
bronze—bent to angular cross section, with 75
provision of a rounded flexible tongue 21 for
yielding engagement with the top of the
flange 18, on the closure 6, and an upright
anchorage portion 22 for lodgement and re-
tention in a counter recess 19^a of the 80
hollow 19.

For outwardly swinging closures, the
threshold or sill of my invention is arranged
as illustrated in Fig. I, i. e., the stop mem-
ber 10 is placed over the base member 9 with 85
the lateral hollow or recess 19 of its vertical
projection 15 facing outwardly, and with its
position determined through abutment of its
downward edge flanges with the ridge 11 of
the base member 9. A suitable cement, con-
ventionally indicated at C, is ordinarily em-
ployed to secure the stop member 10 to the
base member 9; but if desired, screws S may
be used in addition. Placement of the stop 90
member 10 is preferably deferred until after
hanging of the closure 6, so that advantage
may be taken of the versatility afforded by
use of the cement C in securing accurate
alignment with the closure 6 in both horizon-
tal and vertical directions. As shown in Fig. 95
100

I, the bottom flange angle piece 18 of the closure contacts with the outer edge of the stop projection 15 of the member 10, when the door or sash 6 is in closed position; while by cooperation between the flexible strip 20 within the hollow 19 and the horizontal flange of said angle piece 18, a perfect weather-tight seal is formed with the threshold or sill 5. **Drip water due to condensation of moisture on the inside of the door or sash 6, when in closed position, is directed by the top slope of the stop projection 15 of the member 10, into the gutter 17 wherein the accumulation may either be allowed to evaporate, or from which it may be drained in any convenient manner as desired or found most expedient in practice.**

For inwardly opening closures, the threshold or sill 5 is arranged in accordance with Fig. II. Here it will be observed that the position of the stop member 10 is reversed with the hollow 19 of its stop projection 15 facing inward and its position determined through abutment of but one of its downward edge flanges with the medial ridge 11 of the base member 9. To suit the reversed position of the stop member 10, the angle piece 18^a is in this instance secured to the flange 8^a of the bottom rail 8 of the closure 6, instead of the flange 8^b as before. As in the first adaptation, drip water from the closure 6 collects in the trough 17, but the latter is now on the outside of the door structure. Water thus collected may be permitted to run out of the ends of the gutter 17 or sluice holes such as shown at 23 may be provided at intervals along the length of the projection 16. As a further safeguard against entry of water, the closure 6 is provided with an inclined baffle 25 to overhang the gutter 17. In case water should get by the sealing strip 20 when the door or sash 6 is in closed position, the same would be caught in a second gutter 26 formed between the ridge 14 of the base member 9 and the contiguous edge of the stop member 10. This gutter 26 will also trap the drip water resulting from condensation on the inside of the closure 6.

From the foregoing it will be seen that I have provided a very simple threshold or sill structure that is interchangeable by virtue of the reversibility of its stop abutment member. The threshold or sill is further unique in that no structural changes are necessary in converting it from one condition of use to the other, nor are special tools required in its placement. In addition to the above advantages my invention precludes the necessity for carrying in stock separate thresholds as heretofore necessary for installations in which oppositely swinging doors or windows are specified. It is moreover novel in that it provides for concealment of flexible weathering which is retained in the structure without aid of separate securing devices, as well

as means for trapping water of condensation with avoidance of injury to, or spoilage of interior finishes, hardwood floors, etc.

Having thus described my invention, I claim:

1. A threshold or sill for swinging closures comprising a base member and a stop member with an upstanding abutment for the closure, said stop member being capable of off-center reversible fixture to the base member whereby the threshold or sill is adapted to either outwardly or inwardly opening closures, and longitudinal ridges on the base member predetermining the exact off-center position of the stop member relative to said base member for both conditions of use. 70
2. A threshold or sill for swinging closures comprising a base member with a medial longitudinal ridge, and an associate stop member of channel cross section to bridge the ridge of the base member, said stop member being capable of location laterally off-center to one or the other side of the medial ridge and fixture to the base member whereby the threshold or sill is adapted to either outwardly or inwardly opening closures. 75
3. A threshold or sill for swinging closures comprising a base member of shallow channel-section with a medial longitudinal ridge and a paralleling abutment, and an associate stop member capable of reversible location on and fixture to the base member for adaptation of the threshold or sill to outwardly or inwardly opening closures, said stop member being of channel cross section to bridge the ridge of the base member and having its positions of use, respectively, determined through contact of one or the other of its channel flanges with the ridge or by contact of its flanges with each ridge and the abutment aforesaid. 80
4. A threshold or sill component for swinging closures of channel-section having a stop with a lateral hollow to receive a horizontal edge flange along the bottom of the closure, and a flexible weather strip of angular-section with provision of a rounded flexible tongue concealed within and retained by said hollow for cooperation with said flange on the closure. 85
5. A threshold or sill component for swinging closures of channel-section having a stop with a lateral hollow cross-sectionally configured for concealment of and to retain a flexible weather strip of angular-section with provision of a rounded flexible tongue for cooperation with a horizontal edge flange along the bottom of the closure. 90
6. A threshold or sill component for swinging closures of channel-section having a gutter to trap condensation water dripping from the closure when in closed position, and an upstanding stop abutment for the closure, 95

said stop abutment having its upper surface sloped to drain into said gutter.

7. A threshold or sill component of channel-section adaptable to either outwardly or inwardly opening swinging closures said component having paralleling projections on its upper face jointly forming a gutter to trap and dispose of condensation water dripping from the closure when in closed position.

10. A threshold or sill component of channel-section adaptable to either outwardly or inwardly opening swinging closures, said component having an angle-section abutment with a sloping upper face and a paralleling rib jointly forming a gutter for collection and disposal of condensation water dripping from the closure when in closed position.

15. A threshold or sill component of channel-section adaptable to either outwardly or inwardly opening swinging closure, said component having an outwardly directed angle-section integral abutment affording a stop with a lateral hollow paralleling the 20 web of the channel section to receive a horizontal edge flange along the bottom of the closure in either condition of use.

25. A threshold or sill for swinging closures comprising in combination, a base component of shallow channel-section the web portion whereof slopes symmetrically outwards from a medial ridge, and a stop component likewise of channel-section having spaced projections on the web jointly forming a gutter, one of said projections embodying a lateral portion forming a stop abutment for the closure with a subjacent hollow, the latter for the purpose specified.

30. A threshold or sill for swinging closures comprising in combination, a base component of shallow channel-section the web portion whereof slopes symmetrically downwards at a slight angle to the horizontal, from a medial ridge; one of said symmetrical 35 surfaces being interrupted by a longitudinal rib; and a stop component likewise of channel-section having spaced projections on the web jointly forming a gutter, one of said projections embodying a laterally-directed upwardly-sloping flange to provide a stop abutment for the closure with a subjacent hollow, the latter for the purpose specified.

40. A threshold or sill for swinging closures comprising in combination, a base component of shallow channel-section the web portion whereof slopes symmetrically downwards in opposing directions at a slight angle to the horizontal, from a medial ridge; one of said symmetrical surfaces being interrupted by a longitudinal rib; and a stop component likewise of channel-section having spaced upstanding projections on the web jointly forming a gutter, one of said projections embodying a lateral portion upwardly 45 sloping relative to the gutter to provide a

50 lateral stop abutment for the closure with a subjacent hollow; the aforesaid medial and longitudinal ribs on the base component positively positioning the stop component for outwardly-opening closures, and said longitudinal rib in conjunction with the proximate flange of the stop component establishing an additional gutter when said stop component is positionally reversed for inwardly-opening closures.

55. In testimony whereof, I have hereunto signed my name at Philadelphia, Pa. this 12th day of June, 1928.
